FLUID CONTROL SYSTEM

Maxwell Alpern, Philadelphia, Pa., assignor to
American Engineering Company, Philadelphia,
Pa., a corporation of Pennsylvania

Application May 27, 1932, Serial No. 614,132

10 Claims. (Cl. 110—44)

This invention relates to systems employed in the handling of fluids either in the gaseous or liquid state, and comprises means for controlling such fluids in passing through said systems. 5 In the accompanying drawings the invention is shown in one form which it might take when applied to or embodied in stoker furnaces. This embodiment is only illustrative, however, as the invention is capable of modification and change 10 to permit applying it to other devices, such, for example, as ventilating systems and hot air heating systems.

The present invention contemplates a fluid system comprising a series of ducts through 15 which fluid from a common pressure chamber passes to sectionalized groups of tuyères or grates of a stoker furnace. Control mechanism is associated with each duct for automatically regulating the volume of fluid passing therethrough. This mechanism is so constructed as 20 to independently regulate the volume of fluid passing through each duct in direct proportion to the resistance offered to the free flow of fluid therethrough. Thus, when the resistance to the 25 flow of fluid in a duct increases, the volume of air passing therethrough will also increase, and vice versa; when the resistance decreases the volume of air passing therethrough will also decrease.

In stoker furnaces the density of the fuel bed constitutes the resistance offered to the flow of air through the various ducts. In such devices the depth of the fuel bed varies from front to rear, it having the greatest depth near the front 35 of the stoker and gradually tapers off toward the rear thereof. In furnaces of the type illustrated the ash forms at the top of the incandescent fuel and during operation of the furnace fusion of the ash takes place to a certain extent thereby 40 forming clinkers which also have a tendency to vary the density of the fuel bed. The size of the coal particles also has a tendency to vary the density of the fuel bed. Some fuels also contain a large amount of tar which during the 45 process of combustion form plastic masses making it more difficult for the air to penetrate than other fuels which during the coking stage are of a more porous nature.

The density of the fuel bed, therefore, not 50 only depends upon the thickness thereof, but also upon other conditions, some of which have just been stated. Because of these conditions it frequently happens that an abnormally thin fire will develop in certain portions of the fuel bed. 55 Such portions present the least resistance to the

free flow of air and consequently will receive more air than is necessary for proper combustion of the fuel, and if nothing is done to check such conditions, the incandescent fuel will soon find its way to the grates and may cause serious 5 damage thereto which can only be corrected by extinguishing the fire. This requires taking a boiler off the line so that workmen may replace the damaged parts and obviously results in considerable losses to the user.

One object of the present invention is to 10 eliminate such losses by so regulating the draft air that all portions of the fuel bed will receive proper amounts of air. In case a thin fire should develop in one or more portions of 15 the fuel bed the air supply thereto will be throttled to permit the fuel feeding apparatus to build it up to such an extent that it will again become normally uniform. The invention also functions to supply a greater amount 20 of air to the portions of the fuel bed which become abnormally heavy, thereby increasing the rate of combustion so that these portions will also again assume a normal condition.

The present invention also includes mechanism 25 which automatically functions to permit greater or lesser volumes of air to pass through the entire system depending upon load conditions. In case the load should increase this mechanism will function to permit greater 30 volumes of air to pass through all of the ducts thereby increasing the rate of the combustion of the fuel to meet the increased load conditions. Likewise, when the load decreases this mechanism will also function to decrease the 35 volume of air passing through the system so that at all times the fuel bed will receive the proper amount of air to insure proper combustion of the fuel.

Another object of the present invention, 40 therefore, is to provide a fluid control system which automatically regulates the volume of air passing therethrough in accordance with the load conditions under which the system operates.

A more general object of the present invention 45 is to provide a fluid system which is effective to control the volume of air passing through the entire system in accordance with load conditions, and also to regulate the volume of fluid 50 passing through each branch thereof, in accordance with the resistance offered to the flow of fluid therein.

A more specific object of the present invention 55 is to provide a fluid system having a plurality of

fluid motors, some of which being effective to regulate the volume of air passing through the system as a whole, depending upon load conditions, and others to regulate the flow of fluid in the individual branches thereof in accordance with the resistance offered to the free flow of fluid therein.

A further object of this invention is to provide a draft air control mechanism for stoker furnaces which functions to vary the flow of air to the fuel bed in accordance with load conditions, and also to regulate the flow of fluid in the individual branches thereof in accordance with the resistance offered to the free flow of air by the fuel thereabove.

A further object is to provide a draft air control for stoker furnaces comprising a series of ducts leading from a pressure chamber to sectionalized groups of tuyères, the ducts being so constructed that fuel siftings will be deflected away from the control mechanism and conducted to hoppers positioned beneath the ducts.

Other and further objects will become apparent as the description of the invention progresses.

25 Of the accompanying drawings:

Fig. 1 is a side elevational view taken through one of the retorts of the stoker showing the general arrangement of the fluid control system.

Fig. 2 is a view taken substantially on line 2—2 of Fig. 1, with parts removed to show the mechanism for adjusting the throat dampers of the various air ducts.

Fig. 3 is a view taken on line 3—3 of Fig. 1, showing the arrangement of the fluid control mechanism and the apparatus for handling the fuel siftings.

Fig. 4 is a view taken on line 4—4 of Fig. 2.

Fig. 5 is a sectional side view taken through one of the control boxes.

40 Fig. 6 is a view taken on line 6—6 of Fig. 5.

Fig. 7 is an end view taken on line 7—7 of Fig. 5 with the motor removed to show the construction of the control box.

Fig. 8 is a sectional end view taken through 45 one of the dampers.

Fig. 9 is a view taken on line 9—9 of Fig. 8.

Fig. 10 is an enlarged sectional elevation view taken through the mechanism for adjusting one of the dampers.

50 Fig. 11 is a sectional view taken on line 11—11 of Fig. 12.

Fig. 12 is a view taken on line 12—12 of Fig. 1.

In the drawings the invention is shown applied to an underfeed stoker of the inclined grate multiple retort type, of which, for the purpose of illustration, but five of the retorts are shown. It is apparent, however, that the invention is equally well adapted for use in connection with stokers of any size.

60 Referring to the drawings, 1 indicates the front wall of a furnace equipped with an underfeed stoker of a well known type. This stoker comprises an inclined grate made up of alternating retorts 2 and tuyère rows 3. A series of alternately disposed pushers 4 and dead plates 5 are provided in the bottom of each retort and at the rear of the stoker are provided extension grates 6. The pushers and extension grates are reciprocated to advance the fuel from the top to the bottom of the retorts in accordance with the well known principles of operation of this type of apparatus. The grate terminates in an ash pit 7 from which the ashes may be removed by any suitable apparatus. Beneath the inclined grate structure is a space 8 known as the plenum

chamber, into which combustion air is forced by suitable blower apparatus (not shown) and from which the air passes through the tuyères 3 and extension grates 5 to the fuel bed. The flow of air through the tuyères is controlled by a fluid control system which is designated generally by the numeral 9, and which will be fully described hereinafter. It may be stated here that the walls and bottom of the chamber 8 are sealed so that the air delivered thereto can escape only through the tuyères and grates overlying said chamber.

Fuel is fed to the upper ends of the retorts from hoppers 10 through the medium of main fuel feeding rams 11, Fig. 1, one such ram being provided for each retort. Rams 11 are reciprocated in cylinders 12 with which the hoppers 10 communicate by any suitable power mechanism shown at 13 in such a manner as to force predetermined quantities of fuel emptying into the cylinders 12 from the hoppers 10 into the retorts 2. The main rams 11 and the secondary pushers 4 thus advance the fuel at a predetermined rate to the bottom of the grate structure and the extension grates in turn feed the consumed fuel to the ash pit 7. The pushers 4 and extension grates 6 are also reciprocated by the power mechanism 13 through the medium of the mechanism indicated generally by numeral 14. Since the specific construction of the operation mechanism for the rams and pushers forms no part 30 of the present invention a detail description thereof will not be given. For a complete description of this mechanism reference may be had to United States application of Herbert E. Preston, Serial No. 482,617, filed September 17, 35 1930, and assigned to the American Engineering Company.

The walls of the retorts are comprised of side supporting plates 15 extending substantially the entire length of the stoker having a plurality of 40 removable plates 16 attached along the upper sides thereof upon which the tuyères 3 are supported.

Referring to Fig. 1 it will be seen that each row of tuyères is divided into four groups. Communicating with each group of tuyères is a substantially rectangular air duct or passage 17, which is secured to a respective pair of side plates 15 by welding or any other suitable means. A pair of plates 18 are provided for each duct 17, 50 which extend from the top of the duct to the upper edge of plates 15. In order to prevent the escape of fluid from one duct to another additional plates 19 and 20 are provided, the latter of which is fastened at one end between the adjacent tuyères of adjoining groups and is bent downwardly in close juxtaposition to the plates 16. The lower end of plate 20 is positioned between sections 21 and 22 of plate 19 and is provided with an open slot 23, extending upwardly 60 from the bottom edge thereof so as to straddle bolts 24, which extend through elongated slots 25 provided in sections 21 and 22 of plate 19. The slots 25 are provided in the sections of plate 19 so that when the parts have been arranged in 65 the manner just described the sections 21 and 22 may be extended to bring the side edges thereof into contact with plates 16. The parts are then secured in this position by simply tightening bolts 24. Suitable packing 26 is then placed around 70 the joints to effectively seal the same against air leakage.

As shown in Figs. 1 and 3, the ducts 17 depend from the lower edges of side plates 15 into the plenum chamber 8, and are secured in any suit- 75

able manner intermediate the ends thereof to a shedding plate 27. This plate is substantially rectangular in form and extends across the chamber 8 and inclines downwardly from front to rear thereof. The lower edge of this plate communicates with a chute 28 extending upwardly from a hopper 29. The shedding plate 27 is provided to collect the coal siftings which escape between the pushers 4 and dead plates 5. These siftings gravitate from plate 27 to chute 28 and thence into hopper 29. A second shedding plate 30 also communicates with chute 28 and is provided to deflect the siftings which pass between extension grates 6 into the chute 28. The lower end of each duct 17 has attached thereto a spout 31 which also communicates with hopper 29. The spouts 31 attached to the ducts 17 for the lower groups of tuyères communicate directly with hopper 29, while those leading from the ducts associated with all of the other groups of tuyères communicate with inclined spouts 32, which in turn communicate with the hopper 29. A normally closed damper (not shown) is provided in each spout 31 to prevent the flow of air to the tuyères through said spouts. These dampers may be opened from time to time by any suitable means to discharge the fuel siftings which have accumulated thereon. Chutes 33 are provided at the upper end of spouts 32 for collecting siftings passing through the upper portion of the stoker.

As shown more particularly in Fig. 3, a control box designated generally by the numeral 34 is positioned adjacent to each duct 17 and communicates therewith through a curved passage 35.

Each control box 34 is provided with a pair of dampers 36 and 37, the former constituting an adjustable throat for the control box, which regulates the volume of air passing through an associated duct, and the latter constituting a throat which is controlled by the resistance offered to the free flow of air in said duct. Thus, during operation periods of the furnace a current of air will be flowing from the control box through passage 35 and ducts 17. As shown more particularly in Fig. 3, the wall of each duct 17 opposite 35 is enlarged as shown at 38, forming a pocket into which the fuel siftings descending in duct 17 will be deflected by the current of air passing therein from passage 35. The siftings then gravitate into spouts 31 and are delivered to hopper 29.

By this construction only a small portion of the fuel siftings will enter the control boxes, the quantity thereof being insufficient to interfere with proper operation of the dampers 36 and 37.

Each control box 34 comprises side walls 39 and 40 and end walls 41 and 42, the latter of which inclines inwardly as shown at 43, and then outwardly slightly as shown at 44 in Fig. 5. End wall 41 is substantially vertical and extends from top to bottom of control box 34. Spaced from wall 41 and substantially parallel thereto is a second wall 45. A wall 46 is also provided at the bottom of the chamber defined by the walls 39, 40, 41 and 42. The upper sides of walls 39 and 40 converge as shown in Figs. 6 and 7, and have secured thereto a framework 47 to which is secured the curved passage 35 through which the air from the control box passes to an associated duct 17. The upper ends of walls 41 and 42 are also secured to the framework 47. Depending from the framework 47 are a pair of vertical walls 48 and 49, the portions 50 and 51 of which extend downwardly to substantially the bottom edge of wall 42. An arcuate plate 52 se-

cured at one end to inner side of wall 41 inclines downwardly therefrom and is secured to edges 53 and 54 of walls 48 and 49 respectively. A wall 55 is attached to the vertical edges 56 of portions 50 and 51 of walls 48 and 49 respectively, and also to the lower end of plate 52. A substantially horizontal plate 57 extends between and is suitably secured to side walls 39 and 40, and also to walls 45 and 55. This plate is formed with a concave depression intermediate its ends so as to permit the plate to fit snugly around arcuate plate 52. As shown in Fig. 7, the portions of side walls 39 and 40 adjacent portions 50 and 51 of walls 48 and 49 respectively, terminate upwardly of the bottom edge of said portions and are bent through substantially ninety degrees into contact with the latter to which they are secured by any suitable means. Thus any fuel siftings which may enter the control box through passage 35 are deflected by plate 52 and portion 43 of wall 42 into chamber 57, from which they may be removed from time to time by simply opening a closure 58 provided at the bottom thereof. In the event that it should be desirable to operate the furnace without regulation of the draft air, it is only necessary to open closures 58. The air would then pass directly to the tuyères without having to first pass through dampers 36 and 37.

Fluid from chamber 8 enters each control box 34 through aligned circular openings provided in walls 41 and 45 of said boxes and the volume thereof which passes into the ducts 17 is regulated by throat dampers 36 which now will be described in detail.

Referring more particularly to Figs. 5, 8 and 9, it is seen that each damper 36 is substantially cylindrical in form and comprises a series of fixed blades 59 and a second series of movable blades 60. The blades 59 are arranged in spaced relation around the periphery of the circular openings provided in walls 41 and 45 and extend between and are secured at their ends to said walls. The ends of the movable blades 60 are secured to rims 61 and 62 positioned in spaced relation within the cylindrical chamber defined by the blades 59. The blades 59 and 60 are so arranged that when the damper 36 is adjusted to closed position blades 60 will register with the openings between blades 59 thereby preventing the passage of fluid therethrough. The rims 61 and 62 are provided with hubs 63 and 64 through which a supporting shaft 65 extends and spokes 66 connect the hubs with said rims. A second pair of rims 67 and 68 are provided adjacent to but spaced outwardly from rims 61 and 62 and which are secured to the inner surface of the blades 59 in any suitable manner. These rims are also provided with hubs 69 and 70 respectively and spokes 71 rigidly secure said hubs to the rims. Adjustable thrust bearings 72 and 73 provided in hubs 69 and 70 respectively, engage the opposite ends of shaft 65 to support the blades 60 for movement. In order to prevent leakage of air between blades 59 and rims 61 and 62 the latter are provided with annular flanges 74 and 75. These flanges extend substantially to the inner side of blades 59 but sufficient clearance is allowed therebetween to permit free movement of blades 60 on bearings 72 and 73.

As shown more clearly in Fig. 8, the upper series of fixed blades 59 and the lower series of movable blades 60 of each damper are provided with depending flanges 76. By this construction it is obvious that the frictional resistance to the free movement of blades 60 that may be caused

by siftings lodging on the blades is minimized. The flanges also act as scrapers to remove such siftings from the blades during operation of the dampers.

5 The damper 37 of each control box 34 is similar in construction to the throat dampers 36 and accordingly a detailed description thereof is unnecessary. Referring more particularly to Figs. 10 5 and 6 it is seen that walls 48 and 49 are also provided with aligned circular openings through which fluid may pass to damper 37 after leaving damper 36. Fixed blades 77 extend between these walls in spaced relation around the periphery of said openings and are secured at the ends 15 thereof to said walls in any suitable manner. Like the dampers 36 the dampers 37 are also provided with a series of spaced movable blades 78 positioned within the chamber defined by blades 77 and when said dampers are in fully 20 closed position the blades 78 will register with the openings between blades 77 thereby preventing the passage of air therethrough. Thrust bearings 79 and 80 are also provided which suitably support the blades 78 for movement.

25 From the foregoing description it is seen that fluid from the chamber 8 enters the control boxes 34 and flows in the direction of the arrows shown in Figs. 3, 5 and 6 through said box and into the ducts 17 which conduct it to the tuyères 3 there-
30 above. All of the joints between the various walls of the control boxes 34, as well as those in the passages 35 and ducts 17, are sealed against air leakage so that all of the fluid delivered to the tuyères must pass through this system.

35 The mechanism for adjusting the dampers 36 and 37 will now be described in detail. Referring to Figs. 1 to 4 it is seen that a fluid motor system 81 arranged outside the front wall 82 of chamber 8 is operatively connected to the movable blades 40 60 associated with each throat damper 36 while a separate motor 83 arranged within the chamber 8 is provided for adjusting the movable blades 78 of each damper 37.

The fluid motor system 81 comprises two parallel rows of individual motors 84a, 84b, 84c, 84d, 45 84e, 84f, 84g and 84h, and each row in the present instance has four motors which are connected in tandem. Through the connections shown in Figs. 1, 3 and 4 between the motor system 81 and 50 dampers 36 the combined action of all of the individual motors 84 will be simultaneously transmitted to said dampers. The number of motors 84 employed depends upon the power required to adjust the dampers 36 and it is obvious that any 55 number thereof may be employed without departing from the present invention. Each motor 84 is supported upon angle irons 85 extending outwardly from wall 82 and the base 86 thereof being secured to a pair of said angle irons by any suitable 60 means such as bolts 87, shown in Fig. 2. The angle irons 85 are secured at one end to wall 82 by welding and are supported intermediate their ends by angle irons 85a depending from the inclined portion 88 of wall 82. Angle irons 85a 65 are also secured to wall 88 and to a row of angle irons 85 by welding or any other suitable means.

The motors 84 are similar in construction so that a description of one will suffice for all. Each motor 84 is constructed of sheet metal or any other suitable material and is formed with spaced cylindrical walls 89 and 90 which define an annular chamber 91, for receiving a bell 92. The lower edge of each wall 89 and 90 is secured to a flat annular ring 93 which in turn is secured to the base 86.

It will be noted that wall 89 terminates substantially midway between the top and bottom of the motor and to the upper edge thereof is secured a circular plate 95 having a series of apertures 96. The upper edge of wall 90 has also secured thereto a circular plate 97 which constitutes the upper casing for the motor. A cylindrical casing 98 having an annular flange 99 is closely fitted around wall 90, the flange 99 thereof lying in abutting relation with the upper surface of plate 97. A flange 100 is also provided around the bottom edge of casing 98 which abuts against and is secured to base plate 86. Suitable sealing means is provided between flange 99 and plate 97, and also between flange 100 and base plate 86 to prevent the escape of fluid therethrough. The annular chamber 91 may be partially filled with mercury to prevent the escape of fluid from one side of the bell to the other. It is obvious that the walls 89 and 90 and the annular ring 93 and plate 95 may be formed from a single piece of material if it is so desired.

The lower surface of bell 92 is exposed to atmospheric pressure by virtue of the apertures 96 and 101 provided in plate 95 and base plate 86 respectively, while the upper surface thereof is exposed to the pressure in chamber 8 through the medium of a pipe 102 which, as shown in Figs. 2 and 4, has one end thereof tightly fitted in an opening provided in plate 97 and the other end projected through an opening provided in wall 82. 25 30

Each bell 92 has attached to the under side thereof a rod 103 which operates in suitable guides provided in plates 95 and 86. The lower end of each rod is pivoted to a lever 104 at a point intermediate the ends of the latter. Lever 104 is pivoted at its inner end to a bracket 105 depending from and suitably secured to base plate 86. The outer ends of the levers 104 are provided with couplings 106 to which are adjustably connected a series of connecting rods 107. The levers 104 for all of the motors are the same with the exception of those associated with motors 84b and 84e. These levers extend inwardly of their pivots and the inner ends thereof are also provided with couplings 108 and 109 respectively. A rod 110 is connected at its lower end to coupling 108 and at the upper end thereof to coupling 109. A second rod 111 is also connected to the coupling 109 at its lower end and extends through a guide 112 provided in wall 88. The upper end of this rod is attached to a coupling 113 provided at the free end of the substantially horizontal arm 114 of a bell crank lever 115 pivoted to the lower end of a bracket 116 depending from the control box 34 associated with the top group of tuyères of the central row, as shown in Figs. 1 and 2. A rod 117 is also connected at its lower end to the coupling 113 and at its upper end to a coupling 118 provided on an arm 119 secured to and extending outwardly from the movable blades 60 of damper 36. The other control boxes 34 for the central row of tuyères are also provided with brackets 116 depending therefrom, to which are also pivoted bell crank levers 115. The substantially horizontal arms 114 of these bell crank levers 115 are connected to the rods 111 and 117 by suitable couplings 108 and 109. The lower ends of the rods 111 and 117 are connected to the rods 103 by suitable couplings 106. The upper ends of the rods 103 are connected to the rods 111 and 117 by suitable couplings 107.

trally horizontal arms 114 of these bell crank levers are also provided with couplings to which are attached the lower ends of rods 117. The upper ends of these rods are likewise attached to couplings 118 attached to arms 119 extending from the movable blades 60 of the respective dampers 36. The lower arms 120 of bell crank levers 115 are also provided with couplings 121 to which are secured connecting rods 122. As shown more particularly in Figs. 2 and 9, a second arm 123 ex- 75

tends from each of the movable blades 60 and also has attached thereto a coupling 124 to which are attached rods 125. Thus it is seen that all 5 of the dampers 36 are interconnected and that any movement of the bells 92 of motors 84 will be imparted simultaneously to said dampers. Adjustable connections are provided between the various connecting rods so that any slack between them may be taken up.

10 As shown in Figs. 2 and 4, the base plates of motors 83d and 83h are provided with depending bracket 126, to the lower ends of which are pivoted segmental discs 127. Each disc is provided with an outwardly extending arm having a coupling 128 to which the lower end of a rod 129 is adjustably connected. The upper end of this rod is connected to a coupling 130 provided near the outer end of lever 104. An arm 131 is pivoted to 132 to each disc and is provided with a stud 133 which operates in an arcuate slot 134 provided in said disc. A weight 135 is attached to the lower end of arm 131. This weight is provided with a longitudinal slot which receives the end of arm 131, so that it may be adjustably positioned on said arm. A set screw 136 is provided to secure the weight in its adjusted position on said arm. A second arm 137 is pivoted on the opposite side of disc 127 at 132, and is also provided with a stud 138 which operates in slot 134. A weight 139 is also provided on arm 137 and also contains a longitudinal slot provided therein for receiving said arm and a set screw 140 secures the weight in adjusted position.

From the foregoing description it is seen that 35 the weights 135 and 139 may be adjusted longitudinally of arms 131 and 137 respectively, and also toward and away from each other by virtue of the connections just described so that the desired adjustment may be obtained. Weights 135 and 139 are provided to balance the pressure exerted upon the upper surfaces of the bells 95 which, it will be remembered, communicate with the chamber 8 through the medium of pipes 102. In operation the weights 135 and 139 are positioned to balance a predetermined pressure in the chamber 8. It therefore is seen that in case the pressure in said chamber should increase, the weights will be moved by the motors 84 about the pivot point of discs 127 a distance commensurate 45 to the change in pressure, and will be held in this position until the pressure in chamber 8 again changes. This movement is transmitted through the various connections described hereinbefore to the movable blades of throat dampers 36, which accordingly are adjusted to permit a greater volume of air to pass therethrough. When the pressure in the chamber 8 again becomes normal the weights 135 and 139 will actuate the dampers 36 to normal position and thus restore 55 the balanced condition of the system. On the other hand, if the pressure in chamber 8 falls below normal the balance will again be broken and weights 139 will tend to rotate disc 127 in the opposite direction, which motion through the various connections heretofore described will also be transmitted to the movable blades of throat dampers 36 with the result that the dampers will be moved toward closed position an amount commensurate with the decrease in pressure, thereby 65 decreasing the volume of air passing therethrough. The purpose of this arrangement is to regulate the volume of air passing through the ducts 17 to the tuyères thereabove so that in case the load should decrease the dampers will be partially closed, thereby causing a decreased

volume of air to be delivered to the fuel bed, and vice versa, if the load should increase the dampers will be opened an amount commensurate with the increased load so that more air may flow through the ducts to the fuel bed. The dampers 36 are 5 so adjusted by the mechanism just described that the difference in pressure between the fluid in chamber 8 and that in control box 34 above these dampers will remain substantially constant.

The mechanism for adjusting the dampers 37 10 of each control box will now be described in detail. As pointed out before, an independent motor 83 is provided to adjust the movable blades 78 of each damper 37. Inasmuch as the structure and operation of this mechanism is the same 15 for all of the control boxes a description of one will suffice for all.

Referring more particularly to Figs. 5, 6 and 10, it is seen that each motor 83 is substantially the same in construction as the motors 84 and comprises a base plate 141 supported upon a suitable bracket 142 attached to and extending from a control box 34 in any suitable manner, such as by bolts 143. Each motor comprises spaced cylindrical walls 144 and 145 the lower edges of 20 which are connected to an annular disc 146 which in turn is secured to base plate 141. Circular discs 147 and 148 are secured to the upper edges of walls 144 and 145 respectively, and a cylindrical casing 149 having an annular flange 150 is 25 fitted around the outer wall 145. An annular flange 151 is provided at the bottom edge of casing 149 which rests upon and is suitably secured to the base plate 141. Suitable sealing means are 30 provided between flange 150 and plate 148, and also between flange 151 and base plate 141. A bell 152 extends into the annular chamber 153 defined by walls 144 and 145. The lower side of bell 152 communicates with the fluid in chamber 8 through openings 147a and 141a provided in plates 147 and 141 respectively. The upper surface of bell 152 communicates with the fluid in control box 34 above damper 36 through the medium of a pipe 154. One end of this pipe extends through wall 42 of the associated control 35 box and the other end thereof is tightly fitted into an aperture provided in plate 148. A rod 155 is secured to the central portion of bell 152 and operates in suitable guides provided in plates 147 and 141 respectively. The lower end of rod 155 is pivoted at 157 to a lever 158, the latter of 40 which is pivoted intermediate its ends at 159 to bracket 142. One end of lever 158 has pivoted thereto a rod 160 which is threaded at its lower end to receive a nut 161. A series of weights 162 having apertures extending through the axis thereof are carried by rod 160 and are retained thereon by nut 161. By this arrangement the mass of weights 160 may be varied to suit the 45 conditions under which the device is operated. The other end of lever 158 is provided with a coupling 163 to which the lower end of a rod 164 is adjustably connected. The upper end of rod 164 is also adjustably connected to a coupling 165 provided at the outer end of an arm 166 extending outwardly from the movable blades 78 of damper 37. As shown in Figs. 5 and 10, a closed rectangular box 167 partially filled with a heavy liquid such as mercury, is supported upon lever 158 and extends an equal distance on either side 50 of the pivot 159 thereof.

It will be noted that only a slight clearance space is provided between the inner surfaces of walls 144 and 145 and the cylindrical portion of bell 152. By constructing the motor in this man- 55

ner it is unnecessary to provide a liquid seal inasmuch as insufficient quantities of fluid may escape from one side of the bell to the other to prevent proper operation of the motor. It is sometimes impracticable to employ a liquid seal, especially when the motor is subjected to higher temperatures due to the rapid evaporation thereof. Under such conditions a motor constructed after the fashion shown in Fig. 10 is preferable.

10 The operation of the mechanism just described will now be briefly stated. It will be remembered that the upper surface of each bell 152 is subjected to the pressure in the associated control box 34 above damper 36, while the lower surface thereof is exposed to the pressure in chamber 8. The pressure on the lower side of bell 152 will obviously be greater than that on the upper side thereof due to the restricted opening at the throat of control box 34 through which fluid from chamber 8 must pass. In order to balance this difference in pressure, weights 162 are provided. When the device is placed into operation the mass of weights 162 is regulated so as to balance the bell 152 for a predetermined difference in pressure.

As has been pointed out before, the density of the fuel supported by the groups of tuyères, with which the ducts 17 communicate, changes from time to time thus creating variable resistances to the free flow of air in said ducts. This causes the pressure in control boxes 34 also to change with the result that the motor mechanisms 83 associated therewith will be thrown out of balance. In case the density of the fuel above a group of tuyères should become greater, it is obvious that the resistance to the flow of air in the duct associated therewith will also become greater and that the pressure in the associated control box will increase a corresponding amount. The bell 152 of motor 83 will immediately respond to this change in pressure and will move downwardly. This downward movement is increased by the shifting of the mercury contained in box 167, thus causing the movable blades 78 of damper 37 to move toward open position a greater distance than they would be moved if actuated by the increased pressure alone. Thus, the fuel directly above these tuyères will receive a greater amount of air and the rate of combustion thereof will increase. Due to this increased rate of combustion the density of the fuel will soon be restored to normal and the pressure in the associated control box will decrease and the greater pressure in the chamber 8 will consequently force bell 152 upwardly until it reaches a proper balanced position.

In case a thin fire should develop over a group of tuyères the resistance to the flow of air passing through an associated duct 17 will decrease with the result that the pressure in the associated control box 34 will also decrease. The pressure in chamber 8, however, will remain substantially the same. Therefore, an upward force will be exerted upon bell 152 equal to this change in pressure causing damper 37 to move toward closed position. When this occurs the mercury in box 167 will shift to the other side of the pivot and the force thereof will tend to actuate the movable blades 78 of damper 37 toward closed position a greater distance than they would be moved had they been actuated by the difference in pressure alone. The fuel bed above this group of tuyères will thus receive but little air, and the rate of combustion of the fuel supported thereby will be reduced. Any damage to the tuyères that may have resulted if the rate of combustion was not

checked is thereby prevented. The fuel feeding mechanism operating at the usual rate will soon restore this portion of the fuel bed to a normal condition and the normal pressure in the control box will again be restored. This pressure is immediately communicated to the upper surface of bell 152 and the mechanism will soon adjust itself to a balanced condition and the normal volume of fluid will again pass through duct 17 to the fuel bed.

Thus it is seen that a highly sensitive fluid control mechanism is provided which is wholly automatic in operation, and which insures the delivery of the proper volume of air to each portion of the fuel bed at all times. The mechanism also functions to maintain the fuel bed normally uniform thereby assuring efficient operation of the stoker.

While the illustrated embodiment shows the invention applied to a stoker furnace it is obvious that it is equally well adapted for use in connection with other forms of mechanism. Instead of communicating with a group of tuyères the various ducts may lead to rooms in a ventilating system. In case the resistance to the flow of air should increase or decrease the motor mechanisms would function to either close or open the dampers, as the case may be, so that proper amounts of air would be delivered to each room of the system.

In the illustrated embodiment the ducts are shown to be in communication only with groups of tuyères. However, it is obvious that similar ducts may also be designed to communicate with the extension grates and lower grates, or any other part of the furnace which receives air from the chamber 8. The invention is, therefore, not limited to the specific embodiment shown herein and it is intended that it should be limited only by the scope of the claims which follow.

What is claimed is:

1. In a stoker, the combination of a tuyère chamber comprising spaced walls, a series of tuyère blocks spanning the space between said walls, a pressure chamber, a duct, a control unit of substantially box-like construction for each duct, a compartment formed within said unit, a damper mounted in the outer walls of said unit, and a second damper mounted in the walls of said compartment, said parts being so constructed and arranged that fluid must pass through both dampers of said control unit before entering said duct.

2. In a stoker, the combination of a tuyère chamber comprising spaced walls, a series of tuyère blocks spanning the space between said walls, a pressure chamber, a duct extending into said pressure chamber from a group of said tuyère blocks, said duct having a restricted throat opening, a damper in said duct, means for adjusting said damper in proportion to the resistance offered to the flow of fluid in said duct, said last mentioned means comprising a fluid motor having a floating bell, means connecting one side of said bell with said pressure chamber and means connecting the other side of said bell with the throat of said duct, means operatively connected to said motor for balancing said bell for a predetermined differential pressure, and additional means associated with said motor for actuating the same a greater distance in either direction than it would be operated by the change in differential in pressure alone.

3. In a stoker, the combination of a tuyère chamber comprising spaced walls, a series of tuyère blocks spanning the space between said

walls, a pressure chamber; a duct extending into said pressure chamber from a group of said tuyère blocks, said duct having a restricted throat opening, a damper in said duct, means for adjusting said damper, said last mentioned means comprising a fluid motor having a floating bell, means connecting one side of said bell with the said pressure chamber and means connecting the other side of said bell with said duct near the throat thereof, means operatively connected to said motor for balancing said bell for a predetermined differential pressure, said last mentioned means comprising a pivoted lever having a weight at one end thereof, means operatively connecting the bell to said lever, and additional means provided on said lever for actuating said bell in either direction depending upon the change in said differential pressure, said last mentioned means comprising a closed vessel 10 partially filled with a heavy liquid supported on said lever and extending an equal distance on either side of the pivot thereof, said last mentioned means being so constructed and arranged that when said lever is tilted in either direction 15 due to a change in the differential pressure to which said bell is subjected the liquid therein will shift in said vessel thereby imparting a greater movement to said bell than would be imparted thereto by the change in differential pressure alone.

4. In an underfeed stoker comprising spaced pairs of spaced walls defining parallel retorts, a row of tuyère blocks spanning the space between each pair of retort walls and forming therewith 20 tuyère chambers, means dividing each of said tuyère chambers into a plurality of compartments each of which is subjacent a group of said blocks, means forming a pressure chamber, a duct extending into said pressure chamber from each 25 compartment and having an adjustable throat damper operable to provide communication with said pressure chamber, automatic means operable in response to changes in pressure in said pressure chamber for simultaneously adjusting all of said throat dampers, a second damper provided in each duct, and an independent automatic 30 means for each damper operable independently of each other and in response to changes in the differential pressure existing between said pressure chamber and the discharge side of said 35 throat dampers for automatically adjusting each of said last mentioned dampers to throttle the flow of fluid therethrough in inverse proportion to the resistance offered to the flow of fluid 40 through the fuel bed supported by the tuyères.

5. In a furnace stoker, the combination of a combustion grate, comprising a series of tuyère blocks, of means forming a pressure chamber beneath said combustion grate, means dividing 45 said tuyère blocks into a plurality of groups, one or more ducts extending into said pressure chamber from said groups of tuyère blocks, a control unit for each of said ducts having a throat damper and a control damper, automatic means 50 responsive to changes in pressure in said pressure chamber for adjusting said throat dampers, and additional automatic means responsive to the changes in the differential pressure existing in said pressure chamber and the discharge side 55 of said throat dampers for adjusting said control dampers.

6. An underfeed stoker comprising spaced walls, defining parallel retorts, a row of tuyère blocks spanning the space between each pair of 60 adjacent retort walls and extending lengthwise

of said retorts, means forming a pressure chamber, means dividing the tuyère blocks of each of said rows into groups, means extending into said pressure chamber from each of said groups of tuyère blocks forming passages for draft air, 5 a throat damper for each of said passages, means interconnecting said throat dampers for simultaneous operation in the same direction, means for operating said throat dampers including a fluid motor system responsive to changes in 10 pressure in said pressure chamber, adjustable means operatively connected to said motor system to balance the system for a predetermined pressure in said chamber, a second damper provided in each of said passages, and independent 15 means for actuating said second dampers.

7. An underfeed stoker comprising spaced walls, defining parallel retorts, a row of tuyère blocks spanning the space between each pair of adjacent retort walls and extending lengthwise 20 of said retorts, means forming a pressure chamber, means dividing the tuyère blocks of each of said rows into groups, means extending into said pressure chamber from each of said groups of tuyère blocks forming passages for draft air, 25 a throat damper for each of said passages, means interconnecting said throat dampers for simultaneous operation in the same direction, means for operating said throat dampers including a fluid motor system responsive to changes in 30 pressure in said pressure chamber, and adjustable means operatively connected to said motor system to balance the system for a predetermined pressure in said chamber.

8. An underfeed stoker comprising spaced walls, defining parallel retorts, a row of tuyère blocks spanning the space between each pair of adjacent retort walls and extending lengthwise of said retorts, means forming a pressure chamber, means dividing the tuyère blocks of each of said rows into groups, means extending into said pressure chamber from each of said groups of tuyère blocks forming passages for draft air, a throat damper for each of said passages, a second damper provided in each of said passages, independent operating means for each of said second dampers, responsive to the changes in the differential pressure existing between said pressure chamber and the discharge side of the respective throat dampers to throttle the flow of air therethrough in inverse proportion to the resistance offered to the flow of air through the fuel bed supported by the tuyère blocks, and additional means operatively connected to each of said operating means for actuating said second dampers.

9. In a stoker, the combination of one or more tuyère chambers formed by spaced side walls and a series of tuyère blocks spanning said walls, a pressure chamber, a duct extending into said pressure chamber from each tuyère chamber, said duct having a restricted throat opening, a damper in said duct, a fluid motor connected to said damper and having a fluid connection to said pressure chamber and to the throat of said duct for adjusting said damper in proportion to the resistance offered to the flow of fluid in said duct, means operatively connected to and balancing said motor for a predetermined differential pressure between said chamber and throat, and additional means cooperating with said motor operative to actuate said motor and damper a greater distance in either direction than they would be actuated by the change in differential pressure alone.

10. In a furnace stoker, the combination of a

combustion grate, comprising a series of tuyère blocks, of means forming a pressure chamber beneath said combustion grate, means forming a plurality of tuyère chambers each underlying a group of said blocks, a duct extending into said pressure chamber from each tuyère chamber, a control unit for each of said ducts having a throat damper and a control damper, automatic means

responsive to changes in pressure in said pressure chamber for adjusting said throat dampers, and additional automatic means responsive to the changes in the differential pressure existing in said pressure chamber and the discharge side of said throat dampers for adjusting said control dampers. 5

MAXWELL ALPERN.
